UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

IMPULSE-CONTROLLING SYSTEM.

1,353,517.

Specification of Letters Patent. Patented Sept. 21, 1920.

Application filed August 19, 1918. Serial No. 250,510.

To all whom it may concern:

Be it known that I, HENRY P. CLAUSEN, a citizen of the United States, residing at Mount Vernon, in the county of Westchester and State of New York, have invented certain new and useful Improvements in Impulse-Controlling Systems, of which the following is a full, clear, concise, and exact description.

10 This invention is an improvement in impulse controlling systems and has particular reference to means for controlling the recording and establishment of connections in telephone exchanges utilizing selectively operable switching devices.

In the operation of telephone sub-exchanges, such as private branch exchanges attended by an operator, and where the main exchange is arranged on a full automatic basis, it has been customary for the operator to make a temporary memorandum of the called number. With a large number of trunk circuits between the private branch exchange and a main automatic exchange, 20 means are necessary for permitting the operator to connect with an idle trunk circuit and dial for the desired line. Heretofore, this has usually been accomplished by associating an ordinary calling device with the 25 trunk circuit and then dialing the wanted number, it being necessary to repeat the operation should the wanted line be busy.

It is proposed, in the present invention, to make a permanent record of a desired 30 number, which record is designed to control the sending of impulses as often as desired. To this end, use is preferably made of a perforating mechanism designed to be placed upon a telephone switchboard to enable the 35 operator to perforate a card with spaced groups of openings corresponding to the digits of the called number, said mechanism being operated by an arrangement having characteristics of a calling device. In transmitting a call, the card is associated with a 40 trunk circuit by mounting the same upon a rotatable element designed to be actuated by the operator and engaging said card is a contact spring, one end of which moves into and out of the perforations in the card so 45 that the spring will be given necessary vibratory movement to make and break a circuit and thus transmit impulses to the line cor-

responding to the digits of the desired number.

An object of the invention is to provide an improved perforating mechanism by which the operator is enabled to quickly perforate a card with groups of openings that correspond to the digits of the wanted number and thereby provide a permanent record which may be readily and repeatedly associated with the transmitting mechanism.

Another object is to avoid the necessity of repeating the desired number, by the use of the ordinary calling or dialing device, should the wanted line be busy, by providing a transmitting apparatus into which the permanent record may be inserted and quickly operated to send impulses to the line.

The inventive idea involved is capable of receiving a variety of expressions, one of which, for the purpose of illustrating the invention, is shown in the accompanying drawings; but it is to be expressly understood that said drawings are employed only to facilitate the description of the invention as a whole and not to define the limits thereof, reference being had to the appended claims for this purpose.

In the drawings:—Figure 1 is a plan view of the perforating mechanism showing the circuits for energizing the electromagnets thereof; Fig. 2 is a vertical sectional view through a portion of the perforating mechanism including the supporting frame for the electromagnets; Fig. 3 is a plan view of the transmitting mechanism; Fig. 4 is a side elevation thereof, partly in section, and illustrating the means for sending the impulses to the line; Fig. 5 is a plan view, partly in section, of an operator's board and showing the perforating and transmitting mechanisms applied thereto.

The invention is shown in the drawings in what is now believed to be its preferred form and by particular reference to Figs. 1 and 2, it will be seen that the perforating mechanism comprises a segmental supporting frame 1 having an up-standing flange 2 upon its outer curved edge and a similar flange 3 upon its inner edge of less height than the flange 2 and provided at its upper end with an in-turned portion 4 having a plurality of openings 5 therein. Mounted upon the frame are a plurality of electro-

magnets 6 to 15 preferably arranged in two rows, the magnets of one row being disposed in staggered relation with respect to the adjacent magnets of the other row. Each of the magnets has its armature 16 pivoted at 17 to the upper edge of the flange 2 and the free end of said armature is provided with an angularly disposed portion 18 to the end of which is pivoted a punch or perforating 10 pin 19 slideable in one of the openings 5 in the in-turned portion 4 and also through a vertically alined opening 20 in the base of the frame 1. Terminals of the electromagnets are connected by wire 21 to the battery 15 22 and ground.

A mechanism in the nature of an ordinary dialing or calling device is connected to the electromagnets and preferably consists of a dial 23 rotatably mounted upon a shaft 24 having a gear 25 keyed or otherwise secured thereto and which is operatively connected to the gears 26 and 27. The latter gear meshes with the teeth of a large gear 28 mounted upon a pivot 29 and provided with 25 diametrically disposed pins 30 upon which a card or other record sheet 31 is mounted previous to being perforated. The gear 28 is provided adjacent its periphery with a plurality of openings 32 which receive the 30 free end of the punch or perforating pin 19 when the armature 16 is pulled up so that a perforation will be formed in the card 31. In order that rotary movement will only be transmitted to the gear 28 when the dial 23 35 is rotated in the direction of the arrow in Fig. 1, the gear 25 is engaged by spring pressed pawl 33 which locks the train of gears against the reverse movement when the dial 23 is automatically returned to its 40 normal position by a mechanism commonly employed with dialing devices and therefore not shown in the present construction.

Arranged about the dial 23 are a plurality of groups of contacts 6' to 15', connected by wire 34, one end of which terminates in the contact 35 normally spaced from the pivoted contact 36 which is connected to ground. Each of the electromagnets 6 to 15 inclusive is connected to each of the groups 50 of contacts 6' to 15' inclusive by the wires 6" to 15", respectively, so that as the contacts of each group are successively engaged it will be apparent that the respective electromagnet will be energized and its armature pulled up.

The dialing device is provided with a pivoted finger stop 37 having the projections 38 and 39 extending from the pivoted end thereof, the former projection being employed for the purpose of limiting the pivotal movement of the stop by engagement with the pins 40 while the projection 39 has connected thereto a spring 41 which yieldably maintains the finger stop in the normal 60 position shown in Fig. 1. After the finger 65

stop has been operated, as will appear, the same is returned to its normal position both by the action of the spring 41 and a pin 42 carried by the dial which contacts finger stop 37 upon the termination of the return movement of the dial. A wiper 43 is secured to the dial 23 and is so constructed that when the dial is rotated by the operator in a clockwise direction, said wiper will pass freely over the groups of contacts 6' to 15' but 70 upon its return movement the same will engage the outer contact of each group and momentarily force it into engagement with the inner contact, thus closing the circuit between the wire 34 and the respective wires 80 6" to 15". By rotating the dial as stated, the operator's finger will come in contact with the stop 37 and rock the same about its pivot, throwing the projection 38 into engagement with the free end of the contact 36, 85 which will, in turn, engage the contact 35 and connect ground to the wire 34, and upon the release of the dial by the operator the same will reverse its rotation and the wiper 43 will successively close the different groups 90 of contacts in the path thereof, whereby the necessary impulses will be sent over the respective wires 6" to 15" to energize the electromagnets to which they are connected. It will be obvious that when the operator 95 initially rotates the dial 23, there will be considerable movement thereof, depending upon which of the openings in the dial is engaged, before the finger contacts the stop 37, and this movement being imparted to 100 the gear 28 the card 31 will be rotated sufficiently to space each group of perforations made therein from the next succeeding group.

In practice, should the operator receive a 105 call for a wanted number, for instance 138, the card 31 is first placed upon the gear 28 and the opening 1 of the dial engaged by a finger whereby the dial may be rotated in a clockwise direction until the finger engages 110 the stop 37 and rocks the same about its pivot until the projection 38 engages one of the stops 40, whereupon the spring 41 will be thrown off center to exert a pull upon the projection 39 and maintain the stop 37 in 115 its operated position until it is returned to normal by engagement of the pin 42 with said stop when the dial is returned to normal. During this initial movement of the dial, the wiper 43 will have passed the group 120 of contacts 6' without closing the same and the projection 38 will have engaged the contact 36 to close the circuit from ground into the wire 34. Upon the release of the dial, the same is returned to its normal position 125 by the mechanism previously referred to but not shown, and the wiper 43 will momentarily engage the outer contact of the group 6' and close a circuit from ground, contacts 36 and 35, wire 34, contact 6', wire 130

6", magnet 6, wire 21, battery 22 to ground, thus energizing the electromagnet 6 and pulling up its armature 16 to operate the perforator 19 thereof. Upon the return of 5 the dial 23 to normal position, the finger stop 37 is rocked by the pin 42 and the engagement between contacts 35 and 36 broken. The operator then engages the opening numbered 3 and rotates the dial until the finger stop 37 is again engaged, thus moving the wiper 43 past the three groups of contacts 6', 7' and 8', and during this rotation of the dial the gear 28 will be rotated to space the first perforation in the card from the next 10 group to be made therein. Release of the dial will cause the wiper 43 to successively close the contacts 8', 7' and 6', thus energizing the respective magnets to form three perforations in the card. At the end of this 15 operation the dial is again rotated by engaging the finger in the opening numbered 8 and moving the wiper 43 past all of the groups of contacts up to and including the contacts 13' so that upon the return of the 20 dial, eight electromagnets will be energized and a corresponding number of openings formed in card 31, whereupon the card may be removed from the pins 30 and thus provide a permanent record by which the operator 25 may call the wanted line.

It now becomes necessary to associate the card 31 with a trunk circuit whereby the impulses may be sent thereover to operate selectively operable switching devices in the 30 usual manner. The transmitting mechanism employed in the present invention preferably comprises a casing 44 which has inclosed therein a spring motor (not shown) employed for the purpose of rotating the 35 shaft 45 in either direction. Since this spring motor may be of any desired type or form, illustration and detailed description thereof are deemed unnecessary. A winding key 46 is provided for rendering the motor 40 active and the key is so connected to the mechanism within the casing 44 that it is only necessary to give the key a slight turn in a clockwise direction to wind the interior mechanism sufficiently to impart to the shaft 45 substantially a complete revolution. The 45 shaft 45 carries a rotary element 47 in the form of a disk or turn-table upon which is placed the card 31 when it is desired to call the wanted subscriber. In Fig. 5 there is 50 shown an operator's board 48 having four transmitting devices mounted thereon, although it will be understood of course, that any number of these devices may be employed according to the number of trunk 55 circuits connected to the private branch exchange.

The transmitting mechanism further comprises a supporting member 49 having one end pivoted at 50, whereby its other end 60 may be adjusted toward and away from the

card 31 on the disk 47 and the latter end of said supporting member is provided with a roller 52 designed to engage the card 31 when same is being rotated. Preferably between the disk 47 and the member 49, the 65 latter supports a contact spring 51 insulated therefrom and having one end in engagement with the card 31 and disposed in the path of movement of the perforations therein so that as the card is rotated, the 70 free end of the spring 51 will move into and out of said perforations and thus have a vibratory movement imparted thereto. Also supported by the member 49 and insulated therefrom and from the contact 75 spring 51 is a contact member 53 which is normally spaced from spring 51. A wire 54 is connected to the contact 53 and extended to a contact spring 55 preferably secured to the casing 44 and which normally 80 engages contact 56 of a wire 57 leading to ground. This spring 55 is held in engagement with the contact 56 through the medium of an insulated point 58 formed upon the free end of an arm 59 secured to the 85 shaft of the winding key 46. However, when the key is given a slight rotation in order to energize the spring motor, the arm 59 is moved away from the spring 55, which then pulls up and breaks the contact at 90 95 95 until the key 46 returns to its normal position, which occurs immediately upon the release thereof by the operator and before the disk 47 is moved appreciably. This action of breaking the circuit through the 100 wire 54 at contact 56 is designed for the purpose of preventing impulses being sent to the trunk circuit through the contact 53 when the disk 47 is initially rotated by the winding of the motor mechanism, which 105 rotation of the disk occurs in a reverse direction from that necessary to send the impulses over the line in their proper order. As soon as the spring motor has been sufficiently wound to impart approximately a 110 complete revolution to the disk 47, the key 46 and consequently the arm 59, will, as previously described, immediately return to normal position and again engage the spring 55 with the contact 56, whereupon 115 the circuit will be closed at this point and the parts will be in position for operation. The vibration of the spring 51 will cause the same to engage and disengage the contact 53, thus making and breaking the circuit 120 at this point and sending impulses through the wire 60 connected to the spring 51 when the same engages contact 53. An impulse relay 61 is connected to the wire 60 and when energized will pull up its armature 62 and open the circuit through the wire 63 to the switch 64, the latter being normally connected to the armature 62 by the wire 65 at contact 66. The switch 64 is 125 in circuit with the wires 67 of the trunk and 130

when closed by the operator the necessary impulses will be transmitted to said trunk. This trunk may be connected to the operating relays of the selector switch of any well-known type of automatic system.

- 5 In operation, when it is desired to transmit a call over the trunk circuit, the card 31 is placed upon the disk 47 by first swinging the supporting member 49 away from 10 the disk and after the card is in position, said member 49 is returned so as to engage the roller 52 with the card and thus maintain the contact spring 51 in proper position to be vibrated by its passage into and 15 out of the perforations in the card. The switch 64 is then closed and the key 46 operated to energize the spring motor, at which time the circuit will be broken at contact 56 and the trunk circuit remain un- 20 affected by any vibrations of the spring 51 due to its engagement in any of the perforations in the card. Before the card 31 begins to rotate in the reverse direction after being turned by the winding of the motor, 25 the circuit through the wire 54 will again be closed at 55 and 56. As the free end of the spring 51 passes into and out of perforations in the card 31, contact 53 will be engaged and disengaged by said spring, thus 30 successively energizing and deenergizing the impulse relay 61 and transmitting the necessary impulses through the switch 64 to the trunk.

What is claimed is:

- 35 1. An impulse transmitting mechanism including a rotatable perforated record, a contact element movable into and out of the perforations in said record, a second contact element interposed between said record and 40 the first named contact element, and an impulse circuit controlled by said contact elements when the first named element moves into and out of the perforations in said record.
- 45 2. An impulse transmitting mechanism including a perforated record, means for rotating said record in either direction, a contact element movable into and out of the perforations in said record, and an impulse 50 circuit open when said record is rotated in one direction and controlled by the movements of said contact element when the record is rotated in an opposite direction.
- 55 3. In a transmitting mechanism for automatic telephone systems, the combination with automatic switching apparatus including a trunk circuit; of a perforated record sheet, means to rotate the same in either direction, a contact spring engageable with 60 said record sheet and movable into and out of the perforations therein whereby said spring is vibrated, and means operated by the vibrations of said spring for transmitting impulses to said trunk circuit when

said record sheet is rotated in one direction 65 only.

4. In a transmitting mechanism for automatic telephone systems, the combination with automatic switching apparatus including a trunk circuit; of a perforated record sheet, a rotary element upon which said record sheet is adapted to be mounted, a spring motor for rotating said rotary element in both directions, a contact spring movable into and out of the perforations in 70 said record sheet whereby the spring is vibrated, means including a circuit affected by the vibrations of said spring to transmit impulses to said trunk circuit when said rotary element is moved in one direction, 75 and means breaking the second named circuit when said rotary element is moved in the opposite direction.

5. In a transmitting mechanism for automatic telephone systems, the combination 85 with automatic switching apparatus including a trunk circuit; of a perforated record sheet, a rotary element upon which said record sheet is adapted to be mounted, a spring motor rotating said means in both 90 directions, said motor being wound in one direction to render the same active, a contact spring movable into and out of the perforations in said record sheet whereby said spring is vibrated, a circuit to which said 95 vibrations are transmitted whereby to send impulses to said trunk circuit, and means breaking the second named circuit when said motor is wound, whereby to prevent impulses being sent to said trunk circuit. 100

6. In a transmitting mechanism for automatic telephone systems, the combination with automatic switching apparatus including a trunk circuit; of a perforated record sheet, a rotary element upon which said record sheet is adapted to be mounted, a spring motor rotating said means in both directions, said motor being wound in one direction to render the same active, a contact spring movable into and out of the perforations in said record sheet whereby said spring is vibrated, a circuit to which said vibrations are transmitted whereby to send impulses to said trunk circuit, and means associated with the winding mechanism of 105 said spring motor for breaking the second named circuit when said motor is wound to prevent the impulses being sent to said trunk circuit. 110

7. In a transmitting mechanism for automatic telephone systems, the combination with automatic switching apparatus including a trunk circuit; of a perforated record sheet, a rotary element upon which said record sheet is adapted to be mounted, a 120 spring motor rotating said means in both directions, said motor being wound in one direction to render the same active, a con- 125

tact spring movable into and out of the perforations in said record sheet whereby said spring is vibrated, a circuit to which said vibrations are transmitted whereby to send impulses to said trunk circuit, an impulse relay in the last named circuit energized and deenergized by the vibrations in said spring, and means breaking the said last named circuit when said motor is wound to prevent the impulses being sent to said trunk circuit.

8. In a transmitting mechanism for automatic telephone systems, the combination with automatic switching apparatus includ-

ing a trunk circuit; of a perforated record sheet, rotatable means supporting the same, driving means actuating said rotatable means, a spring movable into and out of the perforations in said record sheet whereby the spring is vibrated, a circuit to which said vibrations are transmitted whereby impulses are sent to said trunk circuit, and an impulse relay interposed in the second named circuit between said spring and said trunk circuit.

In witness whereof, I hereunto subscribe my name this 12th day of August, A. D., 1918.

HENRY P. CLAUSEN.
